UNITED STATES PATENT OFFICE

LYLE N. GILLIS, OF ROSE CREST, VIRGINIA, ASSIGNOR, BY DIRECT AND MESNE ASSIGNMENTS, OF ONE-HALF TO THE FLOOROLA CORPORATION, OF BALTIMORE, MARYLAND, A CORPORATION OF DELAWARE, AND ONE-HALF TO ERNEST J. NEWCOMER, OF BALTIMORE, MARYLAND

FLOOR-POLISHING MACHINE

Application filed February 12, 1924. Serial No. 692,295.

This invention relates to floor polishing machines and has special reference to improvements in the floor polishing machine illustrated and described in my prior application filed September 7, 1923, and bearing 5 the Serial Number 661,424.

In the floor polishing machine described in said prior application the pressure of the rubbing elements on the floor was regulated by a spring to which access could be had 10 from the bottom of the machine. In certain forms of the machine this was found to be inconvenient.

One important object of the present invention is to so improve the former machine that the spring adjustments may be made from the top of the machine, thus enabling them to be altered from time to time as may be found expedient in different stages 20 of the operations being performed.

The arrangement of the springs in the foregoing application also has a tendency to considerably increase frictional resistance of the parts and especially of the center or main 25 shaft.

A second important object of the present invention is to so arrange the pressure spring that ball or other anti-friction bearings may be employed for the end thrust of the main 30 shaft.

It is furthermore found that, with the prior arrangement of springs, it was necessary to employ a main shaft in which the diameter varied at different points, this being 35 objectionable in some instances from the points of view of manufacture and economy.

A third important object of the present invention is to provide an improved form of pressure spring arrangement in such a device wherein a main shaft of uniform diameter throughout its entire length may be employed thus contributing to ease and economy of manufacture.

With the above and other objects in view as will be hereinafter apparent, the invention consists in general of certain novel details of construction and combinations of 50 parts hereinafter fully described, illustrated

in the accompanying drawings and specifically claimed.

In the accompanying drawings like characters of reference indicate like parts in the several views, and:

Figure 1 is a plan view of the machine as 55 constructed in accordance with the present invention.

Figure 2 is a section on the line 2—2 of Figure 1.

Figure 3 is a section on the line 3—3 of Figure 2.

Figure 4 is a section on the line 4—4 of Figure 2.

Figure 5 is a section on the line 5—5 of Figure 2.

Figure 6 is a bottom plan view.

The invention in its present form comprises a main housing 10 on top of which is located an upper or reduction gear housing 11. On top of the reduction gear housing and located centrally over the main housing is the motor 12 which has its shaft 13 arranged vertically and projecting downwardly through the bearing 14 into the reduction gear housing 11. On the lower end of the shaft 13 is fixed a pinion 15 which meshes with a gear 16 keyed 70 on a jack shaft 17 having its upper end journaled in a bearing 18 fixed in the top of the housing 11 and its lower end similarly journaled in a bearing 19 fixed in the top of the main housing 10. On the shaft 17, below the gear 16 is a drum pinion 20 which meshes with a gear 21 fixed upon the upper end of the main shaft 22. The lower end of this main 75 shaft is threaded as at 23 and carries a wear adjusting nut 24, the purpose of which will be presently made apparent. It is to be observed that this main shaft is made from a single length of metal, preferably cold rolled 80 steel and is consequently of uniform diameter throughout, it being understood that the cutting of the threads on the lower end does not materially affect the diameter of the steel employed. Splined on the lower part of the main shaft is a spider hub 25 from which 85 radiate the arms 26 terminating in socket ends 27 for the reception of the combined radial and thrust ball bearings 28. Mounted in these ball bearings are the stub shafts 29

90

95

100

which support the carriers 30 for the rubbers or polishers 31, these parts being of the same construction as those described in my prior application before referred to. On the stub shafts are mounted the pinions 32 which mesh with the internal ring gear 33 fixed to the underside of shoulder 33^a formed in the housing 10 by means of the screws 33^b. It will be seen that, while these parts are analogous to the similar parts in the prior application, there is an important difference in that the pinions are thinner than the ring gear so that, while retaining the sliding adjustment in a vertical direction, the revolving weight due to the pinions is lessened.

On top of the hub 25 there is provided a thrust bearing 34 of a suitable anti-friction type and on top of this again is located the pressure spring 35 which is in the form of a leaf spring provided with a centrally disposed opening for the shaft 22. This spring extends diametrically across the main housing 10 and its ends are pressed down by adjusting or tension screws 36 passing through the top of the housing 10 and having easily accessible heads above the housing so that they can readily be screwed up or down even while the machine is in use. Supporting wheels 37 keep the housing 10 off of the floor and permit ready movement of the machine over the floor both in polishing and in transporting the machine from one place to another.

It can now be understood that the tension given the spring 35 regulates the pressure of the rubbers on the floor and that the wear which takes place in these rubbers may be compensated by unscrewing the nut 24 and screwing down the tension screws 36 so as to restore the proper tension to the spring 35.

A lift lever 38 is pivoted to the housing 11 and is provided with a yoke end carrying rollers 39 engaging beneath the gear 21 to raise the spider and rubbers off the floor during transportation of the machine. This lift lever is provided with a pawl and ratchet device 40 to hold the parts raised.

The usual handle 41 is also provided.

It will be seen from the foregoing that the spring adjusting means is easily accessible, friction on the main shaft is greatly reduced by the change of spring arrangement without increasing the height of the machine as would be the case if ball thrust bearings were introduced in the prior machine, and that a simple shaft of uniform diameter is employed instead of the stepped shaft necessary with the former construction. Moreover the construction is thereby greatly simplified.

Having thus described the invention, what is claimed as new, is:

1. In a machine of the character described, the combination of a supporting frame, a shaft mounted therein, rubbing means supported on said shaft, a leaf spring connected

with the shaft and normally exerting pressure on said rubbing means and tension adjusting means interposed between the frame and the leaf spring for regulating the tension of said spring.

2. In a machine of the character described, the combination of a supporting frame, a shaft mounted therein, rubbing means supported on said shaft, a leaf spring normally exerting pressure on said rubbing means, and tension adjusting means engaging approximately the opposite ends of said spring and extending through the frame for operation from the exterior thereof.

3. In a machine of the class described, a housing open at the bottom, a main shaft journalled vertically in said housing, means at the lower end of the main shaft for supporting floor engaging elements, a spring within said housing and extending thereacross, said spring being arranged to exert downward pressure on said means, and tension adjusting means for said spring engaging the spring within the housing and projecting through the housing for operation from the exterior thereof.

4. In a machine of the class described, a housing open at the bottom, a main shaft journalled vertically in and centrally of said housing, a spider at the lower end of said shaft, floor rubbing elements on the ends of the arms of said spider, a leaf spring within said housing and extending thereacross, said shaft passing through said leaf spring and the spring being arranged to urge said spider downwards, and tension screws passing through the top of said housing and engaging the spring adjacent the ends thereof.

5. In a machine of the class described, a housing, open at the bottom, a main shaft journalled vertically in said housing, means at the lower end of the main shaft for supporting floor engaging elements, a spring within said housing and extending thereacross, said spring being arranged to exert downward pressure on said means, tension adjusting means for said spring engaging the spring within the housing and projecting through the housing for operation from the exterior thereof, an anti-friction thrust bearing interposed between the first mentioned means and the spring, and an adjusting nut screwed on the lower end of the shaft to adjust the first mentioned means longitudinally thereof.

6. In a machine of the class described, a housing open at the bottom, a main shaft journalled vertically in and centrally of said housing, a spider at the lower end of said shaft, floor rubbing elements on the ends of the arms of said spider, a leaf spring within said housing and extending thereacross, said shaft passing through said leaf spring and the spring being arranged to urge said spider downwards, tension screws passing through

the top of said housing and engaging the spring adjacent the ends thereof, an anti-friction thrust bearing interposed between the spider and the spring, and an adjusting nut screwed on the lower end of said shaft to adjust the spider longitudinally of the shaft.

7. In a machine of the character described, the combination of a housing, a shaft journaled therein, means connected with said shaft for supporting floor engaging elements, a spring within the housing and extending thereacross, said spring being arranged to exert downward pressure on said means, and tension adjusting means connected with approximately the opposite ends of said spring.

8. In a machine of the character described, the combination of a housing having an internal shoulder, a main drive shaft supported within the housing, a frame mounted on said drive shaft, auxiliary stub shafts journaled in said frame, pinions carried by said stub shafts, a main ring gear fitted beneath said shoulder of the housing, and meshing with the pinions, and screws extending through the ring gear and into the shoulder for holding the ring gear thereto.

9. In a floor polishing machine, the combination of a housing, a drive shaft mounted therein for longitudinal slidable movement, means for moving said shaft longitudinally, brush shafts carried by the drive shaft, a ring gear mounted in the housing, and pinions mounted on the brush shafts and meshing with the ring gear, said pinions being substantially narrower than the ring gear.

In testimony whereof I affix my signature.

LYLE N. GILLIS.
